UNITED STATES PATENT OFFICE

EVAN C. HARTER, OF STURGIS, MICHIGAN

BASE FOR CHAIRS AND THE LIKE

Application filed November 21, 1927. Serial No. 234,668.

This invention relates to chairs and particularly to bases for chairs and the like, and more especially to chairs made principally of metal, for use in factories, offices, and so forth.

An object of this invention is to provide a simple and economical, but strong, chair which is sufficiently yieldable to enable it to adjust itself to considerable irregularities of service so that if the chair is resting upon an irregular surface, it will spring sufficiently to let all of the legs have a bearing thereon.

This and other objects, as will hereinafter appear, are accomplished by this invention which is fully described in the following specification and shown in the accompanying drawings, in which:

Figure 1 is a front elevation of a chair embodying the invention;

Fig. 2 is an enlarged horizontal section on the line 2 of Figure 1; and

Fig. 3 is a vertical section on the broken line 3—3 of Figure 2.

The embodiment illustrated comprises a chair having a base A, a seat B and a back C. The base A is composed primarily of four legs 10 which are preferably tubular and which are secured to spaced spider members 11. A central standard member 12, preferably of tubular form, passes through openings 13 in the spider members 11 and is adjustably secured in place as will later be described. This central standard 12 is secured to the crossed braces 14 which are secured to the under portion of the seat B. The back C is secured to the seat by any suitable side braces 15. The legs 10 which, as was previously stated, are preferably tubular, are formed with vertically parallel upper portions 10^a and with downwardly and outwardly curved lower portions which terminate in gliders or casters 10^b. The upper portions 10^a are provided with openings 10^c on the inside to accommodate ears 11^a on the spider members 11. These ears fit snugly into the openings 10^c and have openings 11^b which are adapted to accommodate pins 16 and are so positioned that when the pins are driven therethrough, the inner portion of the legs 10^a are somewhat deflected so as to firmly

retain the pin 16 in place and also prevent much movement between the spider members 11 and the legs.

At the same time, the spider members 11 are slightly yieldable so that if one of the legs rests upon a high spot in the floor, the whole will yield somewhat so as to give all four of the legs a bearing on the floor. A spacer-plate 17 may also be used to give a little additional stiffness to the legs, if desired.

The central standard 12 is adjustably secured between the spider members 11 by means of a clamp 18 which surrounds this tube and which has ears at its ends through which pass a bolt 19 which may be tightened to secure the clamp about the standard 12. After being tightened, the tube 12 and clamp 18 are freely rotatable, the clamp 18 resting upon the lower spider member and having a bearing thereon.

While I have shown and described but a single embodiment of this invention, it is to be understood that it is capable of many modifications. Changes, therefore, in the construction and arrangement may be made which do not depart from the spirit and scope of the invention as disclosed in the appended claims.

I claim:

1. In a base for chairs and the like, a central vertical rod, spaced spider members having central openings adapted to receive said rod and having outwardly projecting perforated ears, legs having openings through which pass said ears, and pins in said perforations to prevent the withdrawal of said legs.

2. In a base for chairs and the like, a central vertical rod, spaced spider members having central holes adapted to receive said rod and having outwardly projecting perforated ears, legs having openings through which pass said ears, said openings closely fitting said ears, and pins in said perforations to prevent the withdrawal of said legs.

3. In a base for chairs and the like, a central vertical rod, spaced spider members having central holes adapted to receive said rod and having outwardly projecting perforated

ears, legs having openings through which pass said ears, said openings closely fitting said ears, and pins in said perforations to prevent the withdrawal of said legs, one pin extending through the openings in both ears in the same leg.

4. In a base for chairs and the like, a central vertical rod, spaced members having central openings adapted to receive said rod,

10 legs having lateral openings, portions of said members extending through said openings in said legs and being apertured, and pins extending into said apertures in said members and clamping said legs against said members.

15 5. In a base for chairs and the like, a central vertical rod, spaced members having central openings to receive said rod, legs having lateral openings, said members having portions extending through said openings in said legs and being apertured, and pins in the apertures in said members to prevent the withdrawal of said legs.

20 6. In a base for chairs and the like, a central vertical rod, spaced members having central openings adapted to receive said rod, hollow legs having openings in their side walls, portions of said members extending through said openings in said legs and being apertured, and clamping members extending into said apertures in said members and engaging the inner surfaces of said legs and clamping said legs against said members.

25 In testimony whereof, I have hereunto set
30 my hand this 9th day of November, 1927.

EVAN C. HARTER.
